—FIG. 2.

UNITED STATES PATENT OFFICE.

RICHARD A. CLARKE, OF CHATTANOOGA, TENNESSEE.

LIFTING JACK.

Application filed April 30, 1921. Serial No. 465,879.

To all whom it may concern:

Be it known that I, RICHARD A. CLARKE, a citizen of the United States, residing at Chattanooga, in the county of Hamilton and State of Tennessee, have invented certain new and useful Improvements in Lifting Jacks, of which the following is a specification.

This invention relates to quick adjusting 10 lifting jacks.

The primary object of the invention is the provision of a rapid operating lifting jack in which the parts are disposed in cooperating relation to facilitate manipulation 15 of the same.

A further object of the invention is the provision of a lifting jack of the above described character, which is collapsible, permitting the folding of the same in compact 20 form for portability.

A further object of the invention is the provision of a lifting jack of the above described character, which is simple in construction, durable, constructed of standard 25 parts, and one which can be manufactured at a relatively low cost.

Other objects and advantages will be apparent during the course of the following detailed description.

30 In the accompanying drawings, forming a part of this specification, and in which similar reference characters designate corresponding parts throughout the several views,

35 Figure 1 is a side elevation of the improved lifting jack showing the same in operative position.

Figure 2 is a vertical cross sectional view 40 showing the cooperating relation of details of the improved jack.

Figure 3 is a side elevation partly in section of a detail used in operating the improved lifting jack.

45 Figure 4 is a cross sectional view taken on the line 4—4 of Figure 2.

Figure 5 is a cross sectional view taken on the line 5—5 of Figure 2.

Figure 6 is a cross sectional view taken on the line 6—6 of Figure 2.

50 Figure 7 is a cross sectional view taken on the line 7—7 of Figure 2.

In the drawings, wherein for the purpose of illustration is shown the preferred embodiment of my invention, the letter A

designates a vehicle jack, including the base 55 B, having a standard C rigidly mounted thereon, said standard provided with a lifting member or sleeve D. A jack operating means E, is pivotally mounted upon the base B, and adapted for operation by a detachable 60 handle structure F, for operating the lifting member D.

It is preferred that the jack be constructed of standard parts, durably constructed, and to this end the base B comprises a pair of 65 substantially rectangular sections 10 and 11 of wrought iron or some analogous durable material. The abutting faces of the sections 10 and 11 are provided with suitable recesses for receiving the circular standard 70 C; said standard C being rigidly affixed at its lower end 12 in the recesses of said sections 10 and 11, as by rivets or bolts 13, which extend from side to side through the sections 10 and 11, thus riveting said sections together. Suitable V-shaped depressions 14 are provided in the abutting faces of the sections 10 and 11, and forwardly of the base B, for the pivotal mounting of the operating means E, and which will be subsequently described.

The standard C is preferably circular in formation, and provided upon one side thereof with the notches or teeth 15, said teeth being so disposed on the supporting standard 85 C as to provide upper horizontal resting faces 16.

The lifting member D is tubular in formation, and preferably circular, to be reciprocably disposed over the standard C. 90 The sleeve D is in reality a piece of ordinary pipe, and is provided adjacent its lower end with the adjustable pawl structure 16. The pawl structure 16, includes a retaining ring 17 adapted for disposition on the exterior 95 surface of the sleeve D, the same being adjustably clamped thereon in any desired position by the set screw 18. The portion of the member 17 opposite the set screw 18 is provided with a pair of forwardly and downwardly projecting fingers 19, adapted for pivotally supporting a pawl 20. The pawl structure 16 is so positioned upon the sleeve D that when the sleeve is reciprocated over the standard C, the pointed end 21 of the pawl 20 will be forced into contact with the teeth 15 by reason of the weighted end 22 of the pawl. As the sleeve

D is moved upwardly over the standard C, the pointed end 21 will ride freely over said teeth. However, as the sleeve D descends, the weighted end 22 of the pawl 20 will 5 force the end 21 into engagement on an upper horizontal seat 16^a of a tooth 15, and thus prevent the sleeve D from farther descension on the standard C.

An axle or article supporting member 25, 10 is adjustably positioned exteriorly upon the lifting member D, the same preferably comprising a projecting supporting flange 26 having a suitable aperture 27 therein for disposition over the member D. A suitable boss 28 may be formed upon the supporting member 25, opposite the projection 26, for the adjustable disposition of a clamping set screw 29, adapted to engage the sleeve D, whereby the supporting member 20 25 may be maintained in any predetermined position on the sleeve D.

Referring to the jack operating means E, a fulcrum lever 30 thereof is pivotally connected by a pin 31 upon an end thereof in 25 the facing depressions 14 of the base B, whereby said fulcrum lever 30 may be oscillated in a vertical plane toward or away from the standard C. A lifting lever 35 preferably formed of two bars 35^a of sheet 30 material is pivotally connected by a pin 36 engaging said bars 35^a intermediate their ends, whereby said lifting lever 35 may be oscillated upon the upper end of the oscillating fulcrum lever 30 for a purpose to be 35 subsequently set forth. The lifting lever 35 oscillates in the same plane of movement as the fulcrum lever 30, and the forward projecting ends of the bars 35^a are provided with a hooked member 38, se- 40 curely riveted to the ends of said bars 35^a for maintaining said bars in spaced relation. The hook 40 of the member 38 projects forwardly from the extreme ends of the bars 35^a, and as illustrated in the drawings. The fulcrum point 36 of the lifting lever 35 is disposed closer toward the hook 40 than toward the opposite end of said lever. This end of the lever 35 is provided with a forked handle engaging member 45, 50 provided with a relatively flat attaching portion 46 adapted for disposition intermediate the extreme ends of the bars 35^a, and for rigid attachment thereto as by rivets 47. A plurality of fingers or prongs 48 are 55 provided integral upon the attaching portion 46, the same being preferably circular in formation and projecting in vertical succession at acute angles with respect to each other.

60 The handle F is preferably tubular in formation and composed of ordinary pipe. This handle F is preferably formed of a pair of sections 50 and 51 of equal length; a section 50 being provided with a plug 52 riveted therein and provided with a for-

wardly extending screw threaded shank 53, adapted for receiving the internally screw threaded end 54 of the section 51, whereby said sections 50 and 51 may be detachably secured together in rigid relation. The handle F is adapted to receive any one of the prongs 48 in the bores 55 of either of the sections 50 and 51, for rocking the lifting lever 35.

A member 57 is provided for adjustment 75 upon the exterior of the sleeve D, the same being provided with a suitable clamping screw 58 to maintain it in position thereon. This member 57 is provided upon a side opposite the screw 58, with a pair of forwardly projecting spaced fingers 59 and 60. A pin 61 is preferably rigidly disposed upon the outer end of the pins 59 and 60, to provide a suitable aperture 62, for insertion of the forward end of the hook 38; whereby 80 the hooked end 40 of said hooked member 38 may engage the pin 61, and upon rocking of the lifting lever 35 on its fulcrum lever 30, said hook 40 engaging the pin 61, the sleeve D will be reciprocated for lifting 85 any suitable article G such as a vehicle 90 axle.

In operation, the jack structure is positioned beneath the article G to be operated upon, the sleeve D of course having been 95 lowered upon the standard C. In this position the supporting projection 26 of the member 25 will loosely engage below the device or article G to be lifted. The member 57 having been adjusted to the desired 100 height upon the sleeve D, the operator next inserts the sleeve F over one of the prongs 48 of the lifting lever 35, and upon oscillation of this lifting lever 35 upon its pivot point 36, the forward hook 40 upon said lever will 105 engage the pin 61 of the member 57. As the operator places his weight, or a suitable force, upon the handle F, the lever 35 will of course exert an upward pressure upon the sleeve D, sliding the same upwardly over the standard C, until the projection 26 engages the article G, and said article G is raised. As the sleeve D comes to a set position on the standard C, the end 21 of pawl 20 will be disposed over the horizontal surface 16^a of a tooth 15; and when the weight of the operator is released from the lever F, said pawl 20 will engage this surface 16^a to maintain the sleeve D in its 110 adjusted position. Attention is called to the fact that as the lever 35 is rocked upon its pivot 36, the fulcrum 30 will likewise be 115 rocked upon its pivot 31 as illustrated in Figure 1 of the drawings. As the sleeve D is raised upon the standard C, the handle 120 F will of course be lowered toward the floor or the ground surface upon which the jack is positioned. To avoid inconvenience incident to this, the prongs 48 have been provided, whereby the handle F may be de- 125 130

tached from the lower prong, and placed upon any succeeding prong as the sleeve D is raised.

When it is desired to release the jack 5 from beneath the article G, the operator merely applies sufficient force to the lifting lever 35 whereby the pawl 20 is relieved from supporting the weight of the sleeve D, and by raising the weighted end 22 of 10 the pawl 20, the sleeve D can be lowered over the standard C.

The improved jack can be folded in collapsed position and to effect this result, the handle F is detached from the pawl 48, and 15 upon rocking the fulcrum lever 30 upon its pivot 31 toward the standard C, the lifting lever 35 can be placed into substantially parallel alignment with the standard C, to provide a compact arrangement. The sections 20 50 and 51 can be detached and together with the exact structure can be placed in a convenient small enclosure (not shown) for transportation.

Various changes in the shape, size and 25 arrangement of parts, may be made to the form of the invention herein shown and described, without departing from the spirit of the invention or the scope of the claims.

I claim:

30 1. A jack, comprising in combination a base, a substantially circular standard rigidly attached in said base and provided with teeth notched in one side thereof, a tubular sleeve slidably disposed over the said circular standard, an article engaging support adjustably disposed exteriorly on said sleeve, an adjustable pawl on said sleeve adapted for maintaining said sleeve in fixed position by engagement of the teeth on said 35 standard, and means detachably engaging said sleeve for sliding said sleeve upon said standard.

2. A jack, comprising in combination a base, a lifting member reciprocably carried 45 by said base, a fulcrum lever pivoted in a depression in said base and extending upwardly therefrom for oscillation in a vertical plane, a lifting lever oscillatively carried upon the upper free end of said pivoted 50 fulcrum lever, a hook forwardly mounted upon said lifting lever and adapted for engagement with said lifting member, a plu-

rality of prongs formed in vertical succession upon said lifting lever, and means for detachably engaging said prongs whereby said lifting lever may be oscillated for sliding said lifting member. 55

3. A jack comprising in combination a base, a substantially circular standard provided with notched teeth rigidly mounted in one end of said base, a tubular sleeve 60 reciprocably mounted upon said sleeve, an article engaging support adjustably mounted exteriorly upon said sleeve, a pawl adjustably mounted exteriorly upon said sleeve and adapted for engaging the teeth on said 65 standard for supporting said sleeve in adjusted position on said standard, an attaching member adjustably disposed exteriorly on said sleeve, a fulcrum lever pivoted in the end of said base opposite said standard 70 and projecting upwardly therefrom, a lifting lever pivotally mounted upwardly upon the free end of said fulcrum lever, a hook member on one end of said lifting lever adapted for engaging said attaching member 75 on said sleeve, the opposite end of said lever provided with a plurality of prongs, and means for detachably engaging said prongs for rocking said lifting lever whereby said lifting sleeve may be slid upwardly 80 on said standard.

4. As an article of manufacture, a jack lever comprising a pair of spaced longitudinal bars having a hooked member mounted thereon between said bars and projecting 85 from one end thereof, and a forked member mounted between the bars on the end opposite said hooked member, to provide a plurality of engaging prongs in vertical succession thereon, and disposed at acute 90 angles with respect to each other.

5. A jack, comprising in combination a base, a standard rigid on said base, a fulcrum lever pivotally mounted on said base adjacent said standard, a sleeve slidably mounted 95 over said standard, a lifting lever pivotally mounted on the free end of said fulcrum lever, means for connection of said lifting lever and said sleeve, and pawl and ratchet means upon said standard and sleeve to maintain said sleeve in a predetermined position on said standard. 100

RICHARD A. CLARKE.
